Inventor

GEORGE R. HOLBROOK, OF ANSONIA, CONNECTICUT, ASSIGNOR TO
PHELPS, DODGE, AND COMPANY, OF SAME PLACE.

Design No. 3,336, dated January 12, 1869.

DESIGN FOR A CLOCK-CASE.

The Schedule referred to in these Letters Patent and making part of the same.

To all whom it may concern:

Be it known that I, GEORGE R. HOLBROOK, of Ansonia, in the county of New Haven, and State of Connecticut, have invented a new Design for Clock-Case; and I do hereby declare the following, when taken in connection with the accompanying drawing, and the letters of reference marked thereon, to be a full, clear, and exact description of the same, and which said drawing constitutes part of this specification, and represents a front view.

This invention relates to a design for what are termed round-top or Gothic clocks, and consists in the peculiar configuration of the base.

Heretofore this class of clocks has been made with a plain, square base.

To improve this portion of the clock, I form upon

the upper angle of the base an ogee-moulding, as denoted at *a*, in the drawing, and, for further improvement in this class of clocks, I place around the lower panel of the door a gilt moulding, *d*, as also shown in the drawing. The other portions of the clock are of the usual form and design.

Having fully described my invention, What I claim as new, and desire to secure by Letters Patent, is—

The design, herein described, for improvement in the base of clocks.

GEO. R. HOLBROOK.
